BEACH TOGA

Ralph Boryszewski, 67 Northampton St.,
Rochester 6, N.Y.
Filed Nov. 7, 1957, Ser. No. 695,132
2 Claims. (Cl. 2—89)

This invention relates to a bather's beach accessory, and more particularly to a dressing sack or robe adapted for making changes in beach attire, drying after bathing, and capable of utilization as a pair of individual beach spreads, for sun bathing.

The invention is directed to a pair of large terrycloth beach towels or the like, such as are used for beach spreads, and which are adapted particularly for forming a sack or wrap, adapted to be suspended from the wearer's neck, and within which the wearer while thus protected from view may make necessary changes in attire, as required, at bathing beaches and the like, the toweling also providing for drying. The beach towels are separable for individual use as beach blankets or spreads, and are so constructed in relation to one another as to be readily connected along their side marginal edges as to be adapted for the purposes set forth.

The above and other novel features of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

Referring to the drawings wherein like reference characters indicate like parts:

FIGURE 1 is a front elevational view of the beach towels supported by the wearer preparatory to making a change in attire;

FIGURE 2 is a plan view of the inside of one of the towels;

FIGURE 3 is a plan view of the inside of the other of the towels; and

FIGURE 4 is a side elevational view showing the towels shortened at their lower ends for short persons.

Referring to FIGURES 1-3, there is shown a person enclosed within the poncho-like individual dressing sack, composed of two terrycloth towels, of large size, and the front and rear terrycloth towels 10 and 12 of which the same is composed. In practice each towel may be approximately 32" wide and 62" long. The front towel, shown from the inside, as in FIGURE 2, is provided with male snaps 14 and 16 along the upper edge adapted to cooperate with female snaps 18 and 20 on the inside of the towel 12. Such snaps are correspondingly spaced on each towel a suitable distance, so that when the snaps 18 and 14 are coupled together, and the snaps 16 and 20 are also coupled together, the portion of the upper edges 22 and 24 between the respective snaps are of sufficient length to extend around and loosely embrace the wearer's neck, with the sections of the towels 28 and 30, and 31 and 32 adapted, adjacent to the snaps, to rest upon the wearer's shoulders, whereby to support the towels in draped formation, towel 10, in front of the wearer, and towel 12 behind. The towels being of heavy terrycloth or pile fabric weave, are relatively stiff and thus the upper edges, when coupled, extend laterally without substantial droop.

The central portion of the side edges of each towel, for a distance of about 36" are each provided with half of a slide fastener, commonly referred to as a "zipper," the towel 10, having one half of such a slide fastener securing along its edge 34 as at 36, and a second half of a slide fastener securing along the other side edge 38, as at 40.

2

The towel 12 is likewise provided with a half of a slide fastener, along each edge 42 and 44, as at 46 and 48. The slide fastener parts 40 and 46 are preferably of the completely separable type, but disposed so as to match one another, that is, with their starting ends either both at the lower end, or both at the upper end, so that when the starting ends are coupled, and the slide operator of the fastener is run along the length of the slide fastener parts, the two towels will be joined along the central 36" section of their side edges 38 and 42.

Similarly, the slide fastener part 36 and the slide fastener part 48 will be of the completely separable type, and when joined at their lower, or upper, ends however disposed, and the slide operator traversed along their length, the side edges 34 and 44 will be joined along 36" of the central portion of the side edges 34 and 44 of the towels. For convenience it may be desirable to provide the slide fasteners so as to initially fasten at their upper ends, so that the slide fastener operator moves downwardly as the slide fastener parts are brought together.

In order to assure that the towels will be properly joined so that the male snaps 14 and 16 will face the female snaps 18 and 20, the half of the slide fastener 46 may have the slide operator 50, while the half of the slide fastener 36, may have the slide operator 52. Thus, it would be only possible to join the towels, with their inside faces as shown in FIGURES 2 and 3, facing one another, or both oppositely facing, which would at once appear incorrect to the operator. A pocket such as 53 may be attached to the inside face of the towel 10, or to both if desired.

At the upper corners and on the inside face of the towel 10 are additional male snaps 54 and 56 adapted to be joined to female snaps 58 and 60 disposed on the inside face of towel 12, that is, 54 and 58 are adapted to be joined and also 56 and 60 are adapted to be joined.

Additional snaps, male, 62 and 64 are provided midway between the corner snaps 54 and 56, and the upper ends of the slide fasteners on towel 10, and similar female snaps are disposed on towel 12, so that a feminine wearer, may join snaps 64 and 68, and 62 and 66, for additional protection from any tendency of the upper side edges to gape.

On the outside of each of the towels along their lower edges are male snaps 70, 72 and 74, which are adapted, when the lower portions 76 are folded upwardly along the dotted line 77 to couple with male snaps 78, and 80 and 82, whereby the length of the dressing sack is shortened by a suitable amount for use by a shorter person, in the manner indicated in FIGURE 4.

The wearer of the dressing sack, will initially secure snaps 14 and 20, and rest the upper edges so joined on the right hand shoulder. Thereafter snaps 16 and 18 will be coupled, so as to provide like support from the left hand shoulder. Thereafter snaps 54 and 58 will be joined, and also snaps 56 and 60. The side edges are thereafter joined together by operation of each of the slide fastener operators 50 and 56. If desired, snaps 62 and 66, and 64 and 68 may thereafter be joined.

If it be desired to shorten the towels, as for a short person, the lower portions 76 of each towel may be folded on the lines 77, and the snaps 74, 82 and 88, 72 and 78, 70 joined. The spaciousness of the wrap will thus permit the user to manipulate sufficiently within the sack, so as to permit a change of attire, unexposed. The best drying surface of the towels may preferably be on the inside, to assist drying, when changing from wet bathing attire to street clothes.

As a commercial expedient, it may be desirable to make each of the towels as shown in FIGURES 2 and 3 alike, by employing (in FIGURE 2) male snaps at 14, 54 and 62, and complementary female snaps at 64, 56 and

16, of suitable snap fasteners, each comprising two complementary members. Similarly, the towel of FIGURE 3 will be prepared exactly like FIGURE 2, in that snaps 68, 60 and 18 will be male, and 20, 58 and 44 will be female. Thus an individual need only purchase a single towel, and if two or more individuals proceed together on a beach outing and each have individual towels, their two towels in every instance may be used together, by either individual in succession, the snaps 20, 58 and 44 being female and connectable to the male snaps 14, 54 and 62, and in like manner the male snaps 18, 60 and 68, will couple with the female snaps 64, 56 and 16. Thus the towels of FIGURES 2 and 3 will be identical, and each will be readily interchangeable with any towel so constructed.

It will thus be seen that there is provided a pair of ordinary beach towels or spreads which can readily serve the dual purposes set forth, namely, beach spreads for two, or a protected dressing sack useable by a single individual one at a time. Such sack may be referred to as a "Beach 20 Toga."

Although a single embodiment of the invention has been illustrated and described, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. A dressing sack comprising two rectangular sections of absorbent pile fabric of like shape and free of openings and approximately 32" wide, said sections being connected together continuously along the central portion only of their side edges, and along the outer portions only of the edges of one end, whereby to provide an opening for the wearer's head and neck in the center

5 portion of said edges of one end and portions on opposite sides of said neck opening for resting on and support from the shoulders of the wearer, and arm openings disposed between said end edges, and the side edge connected portions, said openings being of a sufficient length whereby a wearer may withdraw each arm into the sack, and vice versa, said dressing sack having a large pocket disposed centrally of and on the inside face of one of said sections, said pocket opening upward toward the head opening, said sack providing adequate space within for the wearer's arms to permit manual change of beach attire wholly within the sack.

10 2. A dressing sack in accordance with claim 1 wherein each of the side edges are joined by slide fasteners comprising complementary separable parts, attached to the 15 respective sections, one of said parts of each slide fastener having an operator, and one of said operator parts being affixed to each of said sections.
